ATTY'S.

UNITED STATES PATENT OFFICE.

NATHANIEL G. SHAW, OF WEST BRIDGEWATER, MASSACHUSETTS, ASSIGNOR OF ONE-HALF TO GEO. E. KEITH COMPANY, OF BROCKTON, MASSACHUSETTS, A CORPORATION OF MASSACHUSETTS.

SHOE.

1,285,426.

Specification of Letters Patent. Patented Nov. 19, 1918.

Application filed November 26, 1917. Serial No. 203,879.

To all whom it may concern:

Be it known that I, NATHANIEL G. SHAW, a citizen of the United States, residing at West Bridgewater, in the county of Plymouth and State of Massachusetts, have invented new and useful Improvements in Shoes, of which the following is a specification.

This invention has for its object to prevent the outer side portion of the vamp of a shoe from acquiring a bulging deformation between the usual stiffened heel and toe portions which are stiffened respectively by a heel counter and a box toe, which for convenience I call the end stiffeners.

It is well known that the outer side portion of the vamp between the end stiffeners is liable to greater bulging deformation than the inner side, such deformation imparting an untidy appearance to the shoe. It is not practicable to prevent this deformation by stiffening the entire region of the outer side portion of the vamp between the end stiffeners, because certain bones of the foot require, for the comfort of the wearer, flexibility of the corresponding portions of the vamp. I have discovered that by stiffening a limited portion of the outer side of the vamp, or that portion which corresponds in position to the center of the fifth metatarsal bone, and leaving flexible unstiffened portions at the rear and front of the stiffened portion, deformation of the outer side of the vamp may be prevented without discomfort to the wearer of the shoe.

My invention is embodied in a shoe having a side stiffener within the outer side portion of the vamp and engaged with the inner sole of the shoe, said stiffener being located between and spaced from the usual heel and toe stiffeners, so that the vamp has flexible unstiffened portions between the side stiffener and the stiffened heel and toe portions, said side stiffener being adapted to prevent deformation of the outer side portion of the vamp between the heel and toe stiffeners.

Of the accompanying drawings forming a part of this specification,—

Figure 1 is a perspective view of a shoe embodying the invention.

Fig. 2 is a section on line 2—2 of Fig. 1.

Fig. 3 is a view similar to Fig. 2, showing a different embodiment of the invention.

Fig. 4 is a perspective view of the side

stiffener and the means for engaging it with the inner sole represented by Fig. 3.

The same reference characters indicate the same parts in all of the figures.

In carrying out my invention as illustrated by Figs. 1 and 2, I provide a side stiffener 12 located within the outer side portion of the vamp 13 and interposed between the vamp and the lining 14. The lower edge of the stiffener is engaged with the inner sole 15 by some of the inseam stitches 16 which secure the vamp to the inner sole and to the usual welt 17.

The stiffener is located between and spaced from the usual end stiffeners, namely, the heel stiffener or counter 18, and the stiffener within the box toe 19. The form and location of the side stiffener 12 are such that the vamp has flexible unstiffened portions between the stiffener 12 and the end stiffeners, the area of the stiffener 12 being such that it is adapted to cover substantially the outer side of the foot at the region of the center of the fifth metatarsal bone. The flexible unstiffened portions of the upper at opposite ends of the stiffener 12 are adapted to bear on bony portions of the foot behind and in front of the center of the fifth metatarsal bone, so that the shoe may be worn without discomfort to the wearer by the stiffener 12.

In this embodiment of the invention the stiffener is necessarily penetrable by the needle of a sewing-machine, which forms the inseam stitches, and its construction is such that it is capable of being softened and rendered flexible prior to the lasting and stitching operations, and of subsequently becoming relatively hard and rigid.

While the stiffener 12 may be made of sole leather and adapted to be softened by moisture, and to subsequently become relatively stiff by drying, I prefer to make the stiffener of fibrous material, such as textile fabric, or felt, and treated with a composition adapted to be softened by a solvent, or by heat, and to become relatively hard and rigid by drying or cooling. For example, the stiffener 12 may be made from a blank of textile fabric, impregnated with a solution containing asphalt, montane wax, or other material, adapted to be softened by a sufficient degree of heat and to become hard by cooling.

Figs. 3 and 4 illustrate an embodiment, in

which the stiffener 12^a is made of material such as sheet metal, and is provided with a shank 19 adapted to bear on the upper side of the inner sole 15, and to be suitably engaged with the inner sole. For example, the shank may be provided at one end with a hook 20 adapted to take over one edge of the inner sole, and with a spur 21 adapted to penetrate a portion of the inner sole. In 10 this case the stiffener bears on the inner side of the lining 14.

The rear and front extremities of the fifth metatarsal bone are nearer the side surface of the foot than the central portion of said 15 bone. The regions of the foot where said rear and front extremities are located, are the regions which require flexibility of the corresponding portions of the vamp. The region of the foot where the central portion 20 of the fifth metatarsal bone is located is not rendered uncomfortable by a stiffener in the corresponding portion of the vamp. The stiffener 12 should therefore be of such form and size and should be so arranged that it 25 will stiffen that portion of the vamp which coincides with the central portion of the fifth metatarsal bone, without stiffening the portions which coincide with the rear and front extremities of said bone.

30 I claim:

1. A shoe having a side stiffener within the outer side portion of the vamp and engaged with the inner sole of the shoe, said stiffener being located between and spaced 35 from the usual heel and toe stiffeners, so that the vamp has flexible unstiffened portions between the side stiffener and the stiffened heel and toe portions, said side stiffener being adapted to prevent deformation of the

outer side portion of the vamp between the 40 heel and toe stiffeners.

2. As an article of manufacture, a side stiffener for shoes comprising a body formed of substantially flat material shaped to conform to the side of the foot and adapted to 45 internally support a portion of the outer side of a shoe vamp between and spaced from the toe and the heel stiffeners thereof, said body having means engageable with the inner sole to retain it in position. 50

3. As an article of manufacture, a side stiffener for shoes comprising a body formed of substantially flat material shaped to conform to the side of the foot and adapted to internally support a portion of the outer 55 side of a shoe vamp between and spaced from the toe and the heel stiffeners thereof, and a shank extending from said body to lie across the inner sole and provided with means to engage said inner sole to retain 60 said body in position.

4. As an article of manufacture, a side stiffener for shoes comprising a body formed of substantially flat material shaped to conform to the side of the foot and adapted to 65 internally support a portion of the outer side of the shoe vamp between and spaced from the toe and the heel stiffeners thereof, and a shank extending from said body to lie across the inner sole, said shank having a 70 free end bent to form a hook portion engageable with a portion of said sole and having a penetrating projection thereon to retain the body in position.

In testimony whereof I have affixed my 75 signature.

NATHANIEL G. SHAW.
